PORTABLE RADIO CABINET

James K. Gerrie, Wilmette, Ill., assignor to Zenith Radio Corporation, a corporation of Illinois

Application April 5, 1957, Serial No. 45,604

Term of patent 7 years

(Cl. D56—4)

The single figure is a perspective view of a portable radio cabinet, showing my new design.

The dominant features of my design reside in those portions shown by means of full lines in the drawing.

The side wall opposite that shown is substantially identical to that shown, and the rear wall is substantially plain.

I claim:

The ornamental design for a portable radio cabinet, as shown and described.
